United States Patent Office.

DANIEL STIRN, OF MILWAUKEE, WISCONSIN.

Letters Patent No. 89,806, dated May 4, 1869.

IMPROVEMENT IN PIANO-FORTES.

The Schedule referred to in these Letters Patent and making part of the same.

To all whom it may concern:

Be it known that I, DANIEL STIRN, of the city and county of Milwaukee, and State of Wisconsin, have invented a new and improved Piano; and I do hereby declare that the following is a full, clear, and exact description of the construction and operation of the same, reference being had to the accompanying drawings, making a part of this specification, in which—

Figure 1 is a section through line x x of fig. 2.

Figure 2 is a plan.

Figure 3 is a bottom view.

Figure 4 is an end view.

In this invention a new form of sounding-board, and cast-iron frame, and a new arrangement of the sounding-board with relation to the cast-iron frame, the strings, and the supports and fastenings for the latter, are employed for the purpose of giving greater volume, purity, sweetness, and brilliancy to the tone.

In the drawings—

B is the sounding-board, which is curved, or arched upward along its centre, like the sounding-board of a violin.

It is attached to a flat, straight bar, b, at its narrow end, and at its wide end to a bar, b¹, straight along its under side, and convex on its upper side, as shown in fig. 4, the sounding-board itself being of uniform, or nearly uniform thickness.

The board B is strengthened by braces b² b², in shape resembling the end-pieces b¹, and attached to the under side of the board, as shown in fig. 3.

The whole is fastened to the under side of the cast-iron frame F F', by means of the screws s s, as seen in fig. 3.

The sounding-board thus extends under the end F' of the cast-iron frame, the latter being, at that part, also arched to correspond to the shape of the former, so that the space between the two, where one passes under the other, is about equal at all points.

At c there is a space between the rear edge of the sounding-board and the rib of the frame, over which the strings pass.

In order to connect the strings directly to the sounding-board, so that their vibrations shall be communicated to it, I attach to it, parallel with the edge f of the frame F F', a curved bridge, D, of wood, or any other suitable material.

Upon this bridge, I set, at the proper intervals, three pins e e e, for each string, (excepting, perhaps, those that are overstrung,) arranging the pins in the manner shown in fig. 2. I pass the strings m m between these pins, in such a manner that they shall bear against the two end ones on one side, and against the middle one on the other, curving slightly to pass around the middle one, as shown in fig. 2.

Pianos thus constructed, have been thoroughly tested by the inventor, and other manufacturers, and are found to possess a tone of much greater power, purity, sweetness, and brilliancy than when constructed as heretofore.

It is obvious that this improvement can be applied to any kind of instrument.

Having thus described my invention,

What I claim as new, and desire to secure by Letters Patent, is—

1. The combination of a concavo-convex sounding-board B with a cast-iron frame, F F', having the part F' arched, to correspond to the shape of the board below, substantially as and for the purpose set forth.

2. The use of the pieces b² b², in connection with an arched sounding-board B, substantially as and for the purpose described.

DANIEL STIRN.
